COMBINATION ASH TRAY, FLOWER AND
CANDLE HOLDER

Jens Jensen, Englewood, N.J.

Application November 9, 1944, Serial No. 562,732

3 Claims. (Cl. 47—41)

1

My invention relates generally to an ash tray or ash receiver, and it has particular relation to an ash tray or ash receiver that may also be used as a combination flower and candle holder.

An object of the invention is to provide a novel ash tray or ash receiver which is simple in construction, efficient in operation and pleasing in appearance; which will present a clean top surface and sanitary appearance at all times; and which will prevent ashes deposited therein from being blown out when the same is placed or being used in a position that is exposed to strong currents of air as when being used out of doors on a porch or veranda.

Another object of the invention is the provision of an ash tray or receiver which may also be used as an ornamental flower and candle holder whereby the flowers and candle may be arranged in a suitable ornamental effect and will be capable of maintaining such arrangement and effect even when exposed to strong currents of air, etc.

Various other and further objects and advantages of the invention, which result in simplicity, economy and efficiency, will be apparent from the following detailed description, wherein a preferred form of embodiment of the invention is shown, reference being had for illustrative purposes to the accompanying drawings, forming a part thereof, wherein like numbers indicate like parts, in which:

Fig. 1 is a top plan view of the assembled container made in accordance with the principles of the invention;

Fig. 2 is a longitudinal sectional view of the assembled container shown in Fig. 1, the same being taken substantially along the line 2—2 thereof, looking in the direction of the arrows;

Fig. 3 is a cross-sectional view of the assembled container shown in Fig. 1, the same being taken substantially along the line 3—3 thereof, looking in the direction of the arrows;

Fig. 4 is another cross-sectional view of the assembled container shown in Fig. 1, the same being taken substantially along the line 4—4 thereof, looking in the direction of the arrows;

Fig. 5 is a top plan view of the tubular insert member, which, in cooperation with the top cover plate, functions as a holder for flowers and a candle; and

Fig. 6 is a bottom plan view of the tubular insert member shown in Fig. 5.

Referring now to the drawings, there is shown in Fig. 1 the invention in assembled form, comprising an open top container 10 made of any suitable rust-proof or rust-resisting metal, having

2

a closed bottom 11, upstanding side walls 12 and curved end walls 13. It will be understood that the container 10 may be made in various other sizes and shapes, and that glass, plastic, crockery or like materials may be substituted for metal, if desired, without departing from the spirit of the invention.

A series of longitudinally spaced protuberances or lugs 14 are formed intermediate each of the upstanding side walls 12 of the container 10. These protuberances 14, when the article is made from metal, may be formed by indenting the outer surfaces thereof inwardly, or in the event the container is being made out of glass, plastic, etc., by molding. They are arranged in a single horizontal plane and are adapted to serve as supporting means for a tubular insert member 15.

A second series of similarly formed protuberances or lugs 16 are provided on the inner surfaces of the upstanding end walls 13, as best shown in Fig. 2, adjacent the upper edge thereof, and are adapted to serve as supporting means for a removable top cover plate 17.

The tubular insert member 15 consists of a bottom plate 18, having a relatively large central opening 19 therethrough, provided with a series of circumferentially spaced upstanding ribs or projections 21 adjacent the edges thereof. These projections 21 are shown as being struck up from the plate when the opening 19 was formed, forming a series of small arcuate and radial flanges 22 therebetween. The remaining surface of the bottom plate 18 is provided with a series of spaced perforations or small openings 23 arranged in rows transversely and longitudinally thereof. The bottom plate 18 has formed integrally therewith upstanding side walls 24, which are suitably connected across their open top by a series of transversely extending ribs or wires 25 spaced longitudinally thereof. The pair of ribs or wires 25 immediately above the large central opening 19, as best shown in Fig. 5, are bent, as indicated at 26, to form a circular opening 27, which is aligned vertically with the bottom opening 19.

The removable top or cover plate 17 is of a size and shape adapted to fit snugly within the open top of the container 10 and rest upon the end supporting lugs 16. It is provided with an ornamental solid platform portion 31 centrally thereof, of which in the embodiment shown is substantially in the form of a cross, having a large circular central opening 32 therethrough in vertical alignment with the openings 19 and 27 of the tubular insert 15 when assembled. The inner surface of the opening 32 has a series of small

teeth-like radial projections 28 spaced circumferentially thereof and formed integrally with the solid portion 31 for engaging the sides of a candle when the same is positioned therein. The remaining surface of the top cover plate 17 is stamped out to form a series of longitudinal slots 33 and ribs 34 arranged alternately and transversely thereof. The material cut from the surface of the plate 17 to form the slots 33 is bent inwardly on opposite sides of the ribs 34, forming integral obliquely and downwardly extending flanges, as indicated at 36, providing a trough-like opening through the slots 33. The slots or openings 33 between adjacent ribs 34 are not wide enough to permit a cigarette to fall therethrough, as indicated at 35 and best shown in Fig. 5.

In assembling the container 10, one end of the tubular insert member 15 is first positioned on its side supporting lugs 14, and the opposite end may then be forced or sprung over the adjacent end supporting lugs 16 until the bottom plate 18 is resting horizontally on all of its supporting lugs 14. The tubular insert member 15 is then more or less locked in between the spaced lugs 14 and 16. However, if the insert member 15 should be constructed of glass, plastic, crockery, etc., it may not be possible to spring it past the end lugs 16 in which event suitable notches will have to be molded therein for clearance purposes. The top cover plate 17 may now be positioned over the tubular insert member 15 on its respective end supporting lugs 16. When it is desired to dismantle the assembled article for cleaning purposes, the forefinger may be slipped through the central opening 32 and the top cover plate lifted upwardly by the forefinger and thumb. The tubular insert 15 may be removed in similar manner.

It will be apparent in using the article as an ash tray or ash receiver that the ashes deposited on the top surface of the plate 17 will fall through the trough-like slots 33, passing through the wires or ribs 24 forming the top of the tubular insert 15 and through the apertures or perforations 23 in the bottom plate 18 to the bottom 11 of the container 10. Manifestly, such ashes will be out of sight and also out of reach of any strong currents of air passing over the top of the container 10. The solid platform portion 31, which may be of any desired design and shape, is not only ornamental but also serves a useful purpose. It may be used for snuffing out in the conventional manner the lighted ends of cigarettes and cigars. The unlighted butts then may be discarded into the container 10 through the opening 31, which, being in vertical alignment with the openings 19 and 27 of the tubular insert 15, will permit them to drop to the bottom 11 of the container 10. The upstanding projections 21 on the top side of the bottom plate 18 of the tubular insert 15 prevents such butts from being lodged between the top and bottom plates of the insert 15.

When it is desired to use the article as a combination flower and candle holder, the bottom of the container 10 may first be partially filled with water before assembling to provide moisture for the cut flower stems. A candle 40, shown in dotted lines in Fig. 2, may be positioned in the aligned openings 32, 21 and 19 until its bottom rests on the flanges 22 of the plate 18 between the upright projections 21. In this position the radial projections 28 of the top cover plate 17 will engage the sides of the candle 40 at a point spaced upwardly from its bottom, thus holding the candle 40 in a fixed vertical position centrally of the container 10. Flowers (not shown) may now be

arranged around the candle 40 in any suitable and pleasing arrangement, with their stems projecting downwardly through the small rectangular top openings 39 formed by the longitudinal bars 34 of the top plate 17 and the transverse ribs 25 forming the top of the insert 15 which now lie adjacent each other in a superimposed position, through the perforations 23 of the bottom plate 18 until they are immersed in the water on the bottom 11 of the container 10. The flowers will stand substantially vertically if the stems are inserted through a perforation 23 that is vertically aligned with the opening 39, but, if desired, may be arranged at a jaunty angle by passing the stems through one of the perforations 23 that is not vertically aligned with the opening 39.

Although I have only described and illustrated in detail one form which the invention may assume, it will be apparent to those skilled in the art that the same is not so limited, but that various modifications may be made therein without departing from the spirit thereof or from the scope of the appended claims.

What I claim is:

1. A new article of manufacture comprising an open top container having internal means intermediate its sides and ends for supporting a tubular insert member, a removable tubular insert member having vertically spaced means including vertically-aligned openings for receiving and holding the stems of flowers and a candle, and a removable cover plate adapted to fit over the top of said tubular insert member and close the open top of said container, said top cover plate having a solid platform portion provided with an enlarged opening, the remaining surface of said top cover plate being divided into a series of alternately disposed ribs and slots, said ribs having downwardly and outwardly extending flanges forming troughs having sloping sides for said slots, the top means of said tubular insert member having ribs dividing its surface into a series of slots extending in a direction transverse to the slots of the top cover plate so that when said article is assembled these respective ribs and slots cooperate to form a series of small rectangular openings arranged in rows longitudinally and transversely of the top cover plate, the bottom means of said tubular insert member having a series of relatively small perforations therethrough adapted to receive the stems of flowers.
2. The combination with an open top container having internal means intermediate its sides for supporting a removable insert member, said insert member having a series of spaced openings in different horizontal planes for engaging flower stems in different vertical planes intermediate their ends and having vertically spaced and aligned openings for receiving a candle, the lower candle receiving opening having means for engaging and supporting the bottom of said candle and means for engaging the sides of said candle at a point spaced from said supporting means for holding the same vertically therein, and a removable top cover member adapted to fit on said open top container having candle receiving means aligned with the candle receiving means of said insert member, said cover member being provided with a series of spaced ribs having downwardly diverging flanges forming a plurality of narrow slots, said ribs being spaced apart a distance such as to support a cigarette therebetween as well as to permit flower stems to pass therethrough.
3. The combination with an open top container

having internal means intermediate its sides for supporting a removable insert member, said insert member having a series of spaced openings in different horizontal planes for engaging flower stems in different vertical planes intermediate their ends and having vertically spaced and aligned openings for receiving a candle, the lower candle receiving opening having relatively long axial flanges for engaging the sides of said candle adjacent its bottom and the upper candle receiving opening having relatively short radial prongs for engaging the sides of said candle at a point spaced from its bottom for holding the same vertically therebetween, and a removable top cover member adapted to fit on said open top container having candle receiving means aligned with the candle receiving means of said insert member, said cover member being provided with a series of spaced ribs having downwardly diverging flanges forming a plurality of narrow slots, said ribs being spaced apart a distance such as to

support a cigarette therebetween as well as to permit flower stems to pass therethrough.
